HUNTING KNIFE OR SIMILAR ARTICLE

Frank Keller, Peoria, Ill., assignor to Keller Kombination Knife, Inc., Meridian, Miss., a corporation of Delaware

Filed Nov. 30, 1965, Ser. No. 88,258

Term of patent 14 years

(Cl. D22—3)

FIG. 1 is a front perspective view of a hunting knife or similar article showing my new design, the movable blades being in closed condition;

FIG. 2 is a front perspective view thereof, one movable blade being shown fully open and the other partly open; and

FIG. 3 is an edge view as seen from the left of FIG. 2.

The side opposite that shown in FIGS. 1 and 2 is a mirror image thereof.

The opposite edge of that shown in FIG. 3 is a mirror image thereof, except that the serrated edge and the can opener edge of the extended screw driver blade are visible.

The design is characterized by a tapered handle, beveled at the ends, the heel end being also curved with the fixed blade end being straight across with three through-bolts at each end arranged in an isosceles triangle, the larger triangle being at the larger end, in combination with the blades as shown.

I claim:

The ornamental design for a hunting knife or similar article, as shown and described.
